(57) **CLAIM**

The ornamental design for an exercise ball, as shown and described.

DESCRIPTION

FIG. 1 is a front perspective view of an exercise ball, showing my new design.

FIG. 2 is a front view thereof.

FIG. 3 is a rear view thereof.

FIGS. 4 and 5 are opposing side views thereof.

FIG. 6 is a top view thereof; and,

FIG. 7 is a bottom view thereof.

The broken lines in the drawings are for the purpose of illustrating portions of the exercise ball, which form no part of the claimed design.

1 Claim, 4 Drawing Sheets**FIG. 1**

FIG. 2**FIG. 3**

FIG. 4**FIG. 5**

FIG. 6**FIG. 7**
